UNITED STATES PATENT OFFICE.

OTTO W. JANTZ AND HERBERT O. JANTZ, OF CINCINNATI, OHIO.

MECHANISM FOR CLEANING METALLIC CONTAINERS.

Application filed May 14, 1925. Serial No. 30,283.

An object of our invention is to provide an efficient mechanism for use in the electrolyte cleaning of metallic containers such as paint pails, ink pails and the like.

Another object is to provide a device of the type mentioned in which a container or pail may be completely cleansed of dried inks, paints or other substances without requiring the usual soaking and manual scraping and scrubbing of the containers.

Another object is to provide a device of the class described which may be expeditiously handled by a workman.

These and other objects are attained by the means described herein and disclosed in the accompanying drawings, in which:

Fig. 1 is an elevational view of the device, parts being broken away and shown disposed within a tank forming part of the device.

Fig. 2 is a view taken on line 2—2 of Fig. 1 and giving a plan view of the cages forming details of our invention.

Fig. 3 is a view taken on line 3—3 of Fig. 2.

Fig. 4 is a view taken on line 4—4 of Fig. 1 showing the contact brushes forming a detail of our invention.

The device comprises an upright or standard 10 extending through a suitable cross beam or support 11 forming a part of a frame structure 12 which is carried by the top of the walls 13 of a suitable tank structure 14. The standard 10 has its upper portion 15 disposed above the frame 12 and its lower portion 16 extending through and below the frame 12 into the interior of the tank 14. The standard 10 may be clamped in the desired position by any suitable means such as threaded flanges 17 disposed on opposite sides of the member 11 of the frame 12. A sliding hinge bearing 18 encircles the lower end 16 of the standard 10 and may be raised and lowered thereon. A suitably perforated lug 19 having a spaced guide 20 passing therethrough and secured at its opposite ends in spaced relation to the portion 16 of the upright 10 by means of suitable spacing blocks 21, serves to preclude the sliding hinge bearing 18 from rotatory movement about the end 16 of the standard 10. The upper end 15 of the standard 10 carries a suitable cross beam 22 having mounted thereon pulleys 23 and 24 from which the cleaning cage of our invention may be suspended by means of a suitable

cable 25 having a counterweight 26 at the free end thereof.

The cleaning cage comprises two members, an exterior cage 27 and an interior 60 cage 28 which are adapted to be disposed on the outside and inside respectively of a container or vessel to be cleaned such as 29 and support bar 30 is pivotally mounted as at 31 upon the sliding hinge member 18 and 65 carries suitable cross beams 32 electrically connected to the support bar 30. The cross beams 32 have flanged ends 33 electrically connected to and supporting the outer cage 27. A second set of cross beams 34 are also 70 electrically connected to the support bar 30 and are secured at their ends to the inner cage 28. The cages 27 and 28 as will be noted are thus suspended in spaced relation from one another upon the bar 30 but both 75 are electrically connected to said bar 30 by means of the cross beams 32 and 34 as just described. On the extreme end of the support bar 30 is a substantially conical tip of 80 insulating material 35, the purpose of which 85 will be explained hereafter. The cages 27 and 28 are provided with strips of insulating material 36 and 37 respectively so that when a pail or container such as 29 is inserted between said cages it will be impossible to make electrical contact between the container 29 and either of the cages 27 or 28. The outer cage 27 is also provided with a pair of insulating strips 38 disposed on diametrically opposite sides of the exterior 90 of the cage 27. A clamp bar 39 of electricity conducting material is hingedly mounted at the ends of one pair of the insulating strips 36 and 38 by means of a suitable hinge structure 40 while the opposite 95 corresponding ends of the second pair of insulating strips 36 and 38 are provided with a suitable latch pin structure such as 41 adapted to receive and lock in position a suitable latch structure 42 carried by the 100 clamp bar 39. The clamp bar 39 is provided intermediate the latch structure 42 and the hinge structure 40 with a series of somewhat resilient contact brushes 43 (see Figs. 1 and 4). An end of the cable 25 carries a pulley 44 which in turn carries a supporting cable 45. The opposite ends 46 and 47 of cable 45 are secured by any suitable means such as hooks to the insulating strip 38 adjacent the latch 41 and the pin 105 31 of the sliding hinge member 18 respectively. The counter weight 26 on the end

of the cable 25 is sufficiently heavy to counterbalance the cage and hinge structure so that a minimum of effort is necessary to raise the cage structure and sliding hinge structure upon the lower portion 16 of the upright 10. From the structure described and shown in Fig. 1, it will be readily apparent that it is possible to raise the sliding hinge structure 18 directly upward and by virtue of the cable 25 operating over pulley 44 that the support bar 30 and the cage structures mounted thereon may be very readily tilted at an angle about the pin 31. The support bar 30 and clamp bar 39 are electrically connected by any suitable means such as flexible conductor cables 48 and 49 respectively of an electrical switching means such as 50. From the foregoing it will be apparent that the inner and outer cages 27 and 28 and the support bar 30 will all be of like polarity while the clamp bar 39 and brushes 43 are of opposite polarity when an electrical current is passed through the cables 48 and 49. It will also be noted that a container such as 29 will be retained in position between the inner and outer cages solely through the resilient action of the contact brushes 43 on the outer bottom wall of the vessel and the insulating conical block 35 on the inner bottom wall thereof. The inner and outer cages are provided with suitable perforations 51 and 52. The tank 14 is adapted to be filled with a solution which will at once form an electrolyte and also exert some natural cleansing action upon a metal container such as 29. For this purpose a mixture of water and caustic soda or soda ash or lye will operate successfully. However, it is desirable to secure a solution that will create a minimum of foam when electrolysis takes place.

The operation of the device is as follows:

It is assumed that a number of ink or paint containers such as 29 are found to have a quantity of very hard and very dry ink or paint adhering thereto and that it is desired to cleanse these vessels in order to again use them. The workman whose duty it may be to cleanse these vessels, will open switch 50 and then raise the cage structure and sliding hinge structure to its uppermost limit on the lower portion 16 of the upright 10 by pulling bar 39 upwardly. He will then be able to move the support bar 30 about its pivotal mounting 31 so that the free ends of the cage structures are disposed above the top of the solution in the tank 16. The workman will then open the latch 41-42 and swing the bar 39 about its hinge 40 whereupon he will be able to insert a vessel or container such as 29 between the inner cage 28 and the outer cage 27 with the insulating point 35 extending into the vessel 29. The bar 39 is then moved about its pivotal mounting 40 to bring the brushes 43

in contact with the bottom of the vessel 29 so that the ends of the brushes 43 make electrical contact with the vessel. Insulating point 35 may serve as an abutment for the vessel. The latch 41-42 is then closed and the vessel remains clamped and electrically connected by the brushes 43. The bar 39 is connected to the negative side of a suitable source of electrical energy of low voltage and high amperage. The cage structure having the container 29 clamped therein is then lowered into the electrolyte in the tank 14 and is manipulated about the pivotal mounting 31 to exhaust all air from within the vessel 29. After the air is exhausted from within the pail the cage is tilted so that particles of ink or paint may be carried away from the pail by gravity. This manipulation is very readily accomplished by grasping the upper end of the bar 39. When the cage structure having the vessel mounted therein has been lowered sufficiently to immerse it completely in the electrolyte, the switch 50 is thrown in following which electrolytic action takes place, the vessel 29 and contact brushes 43 forming the negative electrode while the inner and outer cages 28 and 27 respectively form the positive electrodes spaced from the inner and outer surfaces of the vessel 29. The electric current flowing from the vessel 29 to the perforated cages 27 and 28 will drive off all foreign matter, such as the dried ink, paint or the like from the surface of the vessel and as will have been previously noted, the interior of the vessel 29 is contacted only by the comparatively sharp insulating point 35. The bubbles of gas and the foam caused thereby are permitted to readily dissipate themselves through the perforations 51 and 52 in the inner and outer cages respectively and will tend to carry the loosened particles of foreign matter away from the surface of the container. The slanting position of the inner and outer walls of the vessel will very readily permit the loosened particles to find their way to the bottom of the tank. After the electrolytic action has continued for a time and all of the foreign matter has become loosened from the walls of the vessel 29, the switch 50 may again be thrown out and the cage structure and the vessel contained therein may again be lifted as previously described whereupon the clamp bar 39 may be unlatched and the vessel 29 removed from the cages in a thoroughly cleansed condition.

The source of electrical energy, while diagrammatically shown in the drawings as a generator, would of course be readily supplied from any suitable source.

We claim—

1. In a device of the class described the combination of a support bar, an inner and an outer cage mounted in spaced relation

- from one another upon the support bar and electrically connected to the support bar, a tip of insulating material mounted upon an end of the support bar, a clamp bar adapted to be mounted across the end of the outer cage and electrically insulated therefrom, resilient contact brushes carried by the clamp bar, and means for connecting the support bar and cages to a positive supply line of a suitable source of electrical energy and for connecting the clamp bar and brushes to the negative line of said source of supply.
2. In a device of the class described the combination of a tank for containing an electrolyte, a standard depending in the tank, a sliding member mounted on the standard, a support bar pivotally mounted at its one end upon the sliding member, a pair of substantially concentric cages mounted in spaced relation upon the support bar and electrically connected thereto, a clamp bar removably mounted upon the outermost concentric cage and electrically insulated therefrom, means comprising insulating material carried by the support bar and contact brushes carried by the clamp bar for holding a metallic vessel with its side walls spaced between the cages and free of electrical connection therewith and for electrically connecting said vessel with the clamp bar, and means for lowering and raising the support bar and cages into and out of the tank.
3. In a device of the class described the combination with a tank for containing an electrolyte, of a support bar, a pair of perforate concentric cages mounted in spaced relation upon and electrically connected to the support bar, means for clamping a vessel with its walls interposed between the walls of the cages and free of electrical connection with the cages, and means for connecting the vessel and the cages with negative and positive lines of a source of electrical energy whereby electric current will pass into the vessel through the electrolyte and return through the cages and support bar.
4. In a device for effecting electrolytic cleansing of ink containers and the like the combination with a tank for containing an electrolyte, a cage structure comprising an inner and an outer cage, the walls of said cages being spaced for receiving between them the walls of a container to be cleansed, an electrical clamp bar adapted to contact the container and to clamp the said container in position between the cages free of electrical contact with said cages, and means for electrically connecting the cages to one pole of a source of electrical supply, and means connecting the clamping means and container to the opposite pole of said source of electrical supply.
5. In a device of the class described the combination of a counter-weighted reciprocating pail holder comprising spaced cages and a contact member for clamping a pail in spaced relation to and electrically insulated from the cages and balanced means for permitting rocking of the pail holder in a vertical plane.
6. In a device of the class described the combination of a pail holding cage adapted to extend about the inner and outer walls of a pail, means for raising and lowering the cage and permitting rocking of the cage in a vertical plane, means for electrically connecting the cage and a pail respectively to opposite poles of a source of electrical energy, said cage and pail being normally electrically insulated from one another and an electrolyte container adapted to receive the cage and pail.
7. In a device for cleaning vessels comprising a tank of cleansing fluid, an electrode of a shape simulating the shape of the vessel surface to be cleaned, a source of electrical supply having its one pole connected with the electrode, and means for clamping a vessel adjacent the electrode, electrically connecting the vessel with the other pole of the source of electrical supply, and removably supporting the vessel in the tank.
- In testimony whereof, we have hereunto subscribed our names this 6th day of May, 1925.
